UNITED STATES PATENT OFFICE.

ARCHIBALD S. KINCAID, OF SEATTLE, WASHINGTON, ASSIGNOR TO L. L. PATTERSON,
OF SEATTLE, WASHINGTON.

CHARGE-HUMIDIFYING DEVICE FOR INTERNAL-COMBUSTION ENGINES.

1,397,837.

Specification of Letters Patent.

Patented Nov. 22, 1921.

Application filed October 6, 1920. Serial No. 415,012.

To all whom it may concern:

Be it known that I, ARCHIBALD S. KINCAID, a citizen of the United States of America, and resident of the city of Seattle, in the 5 county of King and State of Washington, have invented certain new and useful Improvements in Charge-Humidifying Devices for Internal-Combustion Engines, of which the following is a specification.

10 My invention relates to devices intended for the purpose of supplying water vapor to the charge of an internal combustion engine.

15 The object of my invention is to provide a simple and effective means for supplying such vapor to the charge, which means will automatically be brought into action without necessity for manually controlling any valves, whenever the engine is running.

20 My invention consists of the novel features of construction and combinations of parts which will first be herein described and then particularly defined by the claims.

25 In the accompanying drawings I have shown the manner of constructing and applying my invention which I now prefer to use.

Figure 1 is a side elevation of an automobile engine within its hood, showing the application of my invention thereto.

30 Fig. 2 is a transverse section through the member by which the supply of water and its vaporization is controlled.

Fig. 3 is a transverse section through that part of the device shown in Fig. 2 which 35 contains the discharge ports.

Fig. 4 is a section through an injection and control device which it has been found desirable to use with my water-vaporizing device.

40 It is a recognized fact among the users of internal combustion engines that they work to better advantage, both as to the production of power, quietness of running, and freedom from carbon deposits, if a small 45 percentage of water vapor be introduced into the charge. If the air taken in as a part of the charge be heavily loaded with moisture, the necessity for adding water vapor thereto may be very largely reduced and possibly 50 substantially eliminated. At most times, however, it is a distinct advantage to add a small percentage of water vapor to the charge.

In devices which have heretofore been designed for this purpose it has been most 55 generally necessary to provide some means for adjusting the device in order to place it into use. In my present invention I have produced a construction by the use of which the device will automatically be brought into 60 action whenever the engine is started and its action will be cut off whenever the engine stops.

In Fig. 1 I have shown in outline a side view of an automobile engine in which 1 represents the intake manifold and 2 the exhaust manifold. A device such as shown in Figs. 2 and 3 is provided for supplying and vaporizing the water which it is desired to inject into the charge, through the injector 70 shown in Fig. 4. This vaporizing device consists of two principal parts, one being a means for automatically controlling the supply of water to the vaporizer and the other being the vaporizer by which this water 75 is turned into steam or aqueous vapor.

Water is supplied to the vaporizing device from any suitable source, as the water-jacket of the engine 3, through a conductor, as the pipe 30, to the water control and vaporizing 80 device shown in Figs. 2 and 3. This device, which is indicated as a whole by the reference character 4, has a float chamber 40 in which is placed a float 5. The inlet to this chamber is herein shown as being at the 85 bottom thereof, to which the water supply pipe 30 is connected in any suitable manner. The particular manner and place of connecting the water supply to the float chamber is immaterial. Where connected at the 90 bottom, as shown in Fig. 2, a valve 50 is shown as closing the inlet opening by a movement from without the chamber 40, upwardly. The particular manner of controlling the water supply is also immaterial, as 95 is the source thereof. I prefer to draw water from the engine's water jacket rather than from a separate tank, for there is less likelihood of this running dry. A tank might be employed for air-cooled engines. 100

The valve 50 is secured to a stem 51 which in turn is secured to the float 5. I have shown this stem 51 as also extending through the cover 41 of the float chamber. In this condition it is possible to force the valve 105 from its seat by pressing upon the project-

ing end of the stem 51, should this at any time be desired. By the above construction the level of water in the controlling chamber 41 will be maintained constant.

5 Extending laterally from the float and controlling chamber 40, is a small vaporizing chamber 42 which has its outer end preferably threaded, so that it may be screwed into and through the side wall of the exhaust 10 manifold 2. This chamber, when in use, is closed except for the ports which will be described. As a convenience in manufacture, the end thereof which extends into the exhaust manifold is shown as being closed by 15 a disk 43 which is inserted during the process of manufacture.

The end of this chamber which is toward the float chamber is separated therefrom by a wall 44, excepting that this wall has a small 20 port 45 connecting the bottom level of the vaporizing chamber 42 with the lower portion of the float chamber. A steam discharge port 61 leads laterally from the top of the vaporizing chamber to join a vertical passage 6, to which is connected a small pipe 60 which extends to and discharges into the inlet manifold 1, at a point between the carburetor and the engine cylinders, through 25 the jet 7. The steam generated in the chamber 42 by the heat of the exhaust is continuously discharged through the pipe 60 into the intake manifold.

The level of water maintained by the float 5 is one which will retain the water level in 30 the vaporizing chamber at substantially half of its height. At a point in the passage 6 there is a small discharge opening 62 connecting this passage and the upper portion 35 of the float chamber. Through this opening 40 steam is discharged before the pressure generated can become an appreciable amount. Vents 46 in the cover 41 permit the vapor to be relieved to the atmosphere, while any water which may be drawn through the 45 opening 62 therewith, remains in the float chamber.

In starting up the engine the heat of the exhaust will very quickly heat the vaporizing chamber 42 sufficiently to produce steam. 50 This will take but a short time as there is but a small amount of water in this chamber at any time. This steam will be discharged through the port 6 and pipe 60 into the intake manifold. If the temperature of the 55 vaporizing chamber should become such as to generate steam at such a rate as to produce any material pressure, the excess steam will be discharged through the opening 62 and vent 46. The float 5, controlling the 60 valve 50, will maintain the water level constantly at the desired point.

There is no valve connected with this device which needs to be attended to when starting or stopping the engine. The entire 65 action is automatic. I prefer, however, to

employ a control valve which will be set at the proper opening, and then left set, much as the setting of the needle valve of a gas carburetor. This control valve 70 I have shown connected with the jet 7. The jet is 70 formed as a T-fitting, into one end of which is secured the jet nozzle 71, of any suitable design. In the opposite end I secure the screw-threaded control valve 70, which may extend past the opening of the lateral branch 75 72, to which is secured the steam pipe 60. By more or less closing down the opening of the steam branch 72 by the valve 70, the amount of steam supplied may be regulated to the exactly proper amount.

80 A device of this sort will supply moisture in the small but continuous amount which is desired in order to secure the best operation of the engine. It will add somewhat to the power of the engine and in addition will 85 prevent the formation of carbon in the cylinders or, if carbon has previously formed therein, it will quickly soften it so that it will soon disappear.

By discharging heated water vapor, or 90 steam, into the intake manifold, the charge is preheated, which increases the ignition capacity of the charge and makes it possible to use with satisfactory ignition, lower and heavier grades of fuel.

95 What I claim as my invention is:

1. A means for automatically supplying water vapor to internal combustion engines comprising a float chamber, a float therein, a supply valve for said chamber controlled 100 by said float, a vaporizing chamber integral with said float chamber and projecting laterally therefrom at an elevation such that a portion only of said vaporizing chamber will be filled with water, said vaporizing chamber having an inlet port from the float chamber below the normal water level, and the vaporizing chamber having a discharge port connecting with its top and a relief port connecting said discharge port and the float 105 chamber above the water level therein, and said float chamber having a vent to the atmosphere above said water level.

2. A device as in claim 1, wherein said discharge port is laterally offset from the 110 vaporizing chamber and leads upward therefrom, and is connected thereto by a substantially horizontal passage.

3. A device as in claim 1, the vaporizing chamber having a wall closing its side next 115 the float chamber, and communicating with the float chamber and the discharge port each by a lateral passage.

4. A device as in claim 1, the inlet port to and the discharge port from the vaporizing chamber being in substantial vertical alignment, and a horizontal baffle extending into said chamber between said ports.

5. A device as in claim 1, the discharge port from the vaporizing chamber being con- 130

neected thereto by a lateral passage which is located above the normal water level therein.

6. A device as in claim 1, the inlet port to and the discharge port from the vaporizing chamber being in substantial vertical alignment, and a horizontal baffle extending into said chamber between said ports, the upper

surface of the baffle being located above the normal water level in the vaporizing chamber.

Signed at Seattle, King county, Washington, this 9th day of July, 1920.
